UNITED STATES PATENT OFFICE.

JOHN C. WATERS AND RICHARD C. WATERS, OF ROMLEY, COLORADO.

CONCENTRATOR.

SPECIFICATION forming part of Letters Patent No. 632,075, dated August 29, 1899.

Application filed June 6, 1898. Serial No. 682,711. (No model.)

To all whom it may concern:

Be it known that we, JOHN C. WATERS and RICHARD C. WATERS, of Romley, in the county of Chaffee and State of Colorado, have 55
invented a new and Improved Concentrator, of which the following is a full, clear, and exact description.

The object of the invention is to provide a new and improved concentrator more especially designed for treating the pulp from stamp-mills or the like, the concentrator being simple and durable in construction and arranged to insure a complete separation of the precious metals from the barren sand or 15 gangue known as "tailings."

The invention consists of novel features and parts and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a plan view of the improvement. Fig. 2 is a front elevation of the same with parts in section. Fig. 3 is a transverse section of the same on the line 3-3 of Fig. 1; and Fig. 4 is a side view of the means for driving the table, the view having some parts in elevation and also other parts in section, such other parts being sectioned slightly to one side of the line 4-4 of Fig. 1.

The improved concentrator is provided with a table A, covered with copper or other suitable covering and made segmental in shape, preferably semicircular, as illustrated in Fig. 1, the table being inclined from the outer peripheral end in a downward direction toward the inner end, as will be readily understood by reference to Fig. 3. The table A is supported at its outer end by legs B, having their upper rounded ends set in similarly-shaped sockets A', secured to or formed on the under side of the table A. The lower rounded ends of the legs B are set in similarly-shaped cups B', held on screw-rods B², screwing in nuts B³, secured to the floor or other suitable foundation, the screw-rod being adapted to be locked in place after the desired adjustment is made by a jam-nut B⁴. Thus by the arrangement described the several legs B can

be readily raised or lowered to give the desired inclination to the table, and at the same time the legs B permit an oscillation of the table, as hereinafter more fully described. 55

The inner end of the table A is provided on diametrically opposite sides with metallic arms A² A³, engaging screw-rods C C', respectively, carried by a head D, mounted to turn on a pivot E, carried by a post F, secured to the floor or other foundation, the center of the pivot forming the center for the segmental table A. Nuts C² screw on the screw-rods C C' to hold the arms in place on the screw-rods, the nuts permitting of adjusting the arms at different heights, if desired, and as indicated in Fig. 2—that is, adjusting the arm A² lower than the arm A³—so that the left-hand side of the table is less in height than the right-hand side of said table. 70

The head D rests on a shoulder E' on the pivot E, and the latter is formed at its lower end with a threaded part E², screwing in the post F to permit of raising or lowering the head D, and consequently the inner end of the table, to give the latter the desired inclination according to the material under treatment. The upper end E³ of the pivot E is made polygonal for the application of a wrench or other tool to permit of conveniently screwing the pivot up or down in the post F for the purpose above mentioned. 75

The head D is provided with a transversely-extending arm D', (see Fig. 3,) on which is bolted one end of a bar G, secured to the under side of the table A at the middle thereof, said bar being formed at its outer end with a slotted head G', engaged at opposite ends by nuts H², screwing on the threaded ends of a rod H', forming part of the device H for imparting a jolting reciprocating movement to the table A, as hereinafter more fully described. The end of the rod H' is provided with a friction-roller H³ in contact with the peripheral surface of a cam H⁴, secured on a shaft H⁵, carrying fixed and loose pulleys H⁶, connected by belt with other machinery for imparting a rotary motion to the said shaft H⁵. On the latter is also secured a fly-wheel H⁷ to insure a steady motion of the shaft. A spring H⁸ is coiled on the rod H' and presses with one end against a collar H⁹, held on the said rod, and 95

with the other end against a part of the frame H¹⁰ supporting the actuating device. The spring H⁸ serves to hold the friction-roller H³ at all times in frictional contact with the 5 peripheral surface of the cam H⁴, so that when the shaft H⁵ is rotated the said cam H⁴ imparts a quick impulse forward and backward to the rod H', and consequently to the table A, without rest between the two movements, a rest then taking place between two 10 impulses, as will be readily understood by reference to the shape of the cam H⁴, as shown in Fig. 4.

The outer end of the table A is provided 15 with an upwardly-extending flange A⁴ for preventing the water and pulp discharged at this portion of the table from flowing over the upper edge thereof, the pulp and water being delivered to the table by a segmental 20 pulp and water distributing trough I, hung on clips I', vertically adjustable in standards I², secured to the floor or other foundation. The trough I is formed with spaced apertures, as is plainly indicated in Figs. 1 and 3, and 25 one side of the trough is extended to discharge the pulp and water toward the flange A⁴, as will be readily understood by reference to Fig. 3. In the middle of the trough I is held a partition I³ for keeping the pulp and 30 the water separate, the pulp being discharged through a pipe J into the left-hand end of the trough while the water is passed through a supply-pipe K into the right-hand end of 35 said trough. The pipe K is provided with a valve K' for controlling the flow of the water through the pipe to the right-hand portion of the trough.

The right hand or concentrate discharge 40 side of the table A is open, a gage L being held adjustably on this side of the table by a clip L' for increasing or diminishing the discharge-opening for the concentrates at this side of the table.

The inner end of the table A is provided 45 with a ridge or flange A⁵, over which the tailings pass into a discharge-trough N, provided with a downwardly-extending pipe N', opening into the funnel O' of the pipe O for carrying the tailings to one side of the machine.

50 The operation is as follows: When the table is intermittently oscillated by the device H, as above described, and the pulp is fed onto the left-hand side of the table and the water on the opposite side thereof, then the quick 55 forward and backward impulse given to the table causes the concentrates to travel over the table in the direction of the arrow a', (shown in Fig. 1,) and during the resting period of the table the concentrates have sufficient time to settle for the next thrust, as described, so that a rapid travel of the concentrates over the inclined table takes place, the 60 concentrates finally passing from the table at the right-hand side thereof between the 65 gage L and flange A⁴. The tailings readily separate from the concentrates on the jolting motion of the table, it being understood that

owing to the position of the distributor the heavier portion of the pulp passes onto the table at or near the left side, while the lighter part of the pulp passes onto the table toward the middle thereof, so that the lighter portion first comes in contact with the water and is readily washed downward over the head A⁵ into the trough N to be discharged into the 70 pipe O, leading the tailings from the machine. The concentrates on reaching the 75 table commence to travel in the direction of the arrow a' and are subjected to the action of the water as they pass on their journey over the table, so that all tailings, sand, &c., are effectively washed out of the concentrates and separated therefrom before the concentrates reach the right-hand or discharge side 80 of the table.

Having thus fully described our invention, we claim as new and desire to secure by Letters Patent—

1. In a concentrator, the combination of a table, a vertical post on which the table is 90 mounted to swing, the table having a segmental form and having a flange at one end, the other end of the table being adapted to discharge the concentrates, a gage mounted at said other end of the table to regulate the 95 discharge thereat, means for supporting the outer portions of the table so as to permit the movement thereof, and a curved trough extending around one edge of the table adjacent to the post, to receive the tailings.

2. In a concentrator, the combination of a 100 post, a segmental table mounted to move on the post, the post being located at the inner edge of the table, means for supporting the outer edge of the table so as to permit the movement thereof, a trough extending around the inner edge of the table and adapted for the discharge of the tailings, a flange secured to one edge of the table at one side of the trough, the opposite edge of the table being adapted 110 for the discharge of the concentrates, a gage mounted at said opposite edge to control the discharge thereat, a second and curved trough located above the outer edge of the table and discharging therefrom, and a partition situated in said trough, to divide the same.

3. In a concentrator, the combination of a 115 post, a vertical pivot mounted thereon, a head mounted to turn on the pivot, two arms attached to the head and extending in opposite 120 directions therefrom and being provided with means for adjusting their relative height, a third arm also attached to the head and projecting between the two first-named arms, a segmental table supported on the three arms, 125 means for supporting the outer edge of the table to permit the movement thereof, a curved trough located at the inner edge of the table adjacent to the post, a flange located at an edge of the table adjacent to the trough, the 130 opposite edge of the table being adapted to discharge the concentrates, and a second curved trough located above the table at the outer edge thereof and serving to discharge

upon the table, the second trough being provided with a partition dividing it into two parts.

4. In a concentrator, the combination of a vertically-sustained pivot, a head mounted to rock thereon, two arms attached to the head and relatively adjustable thereon, the arms extending oppositely from the head, a third arm attached to the head and extending between the two first-named arms, a segmental table mounted on the three arms, means for supporting the outer edge of the table, to per-

mit the movement thereof, a curved trough secured at the inner edge of the table adjacent to the pivot, and a flange at one edge of the table adjacent to the trough, the opposite edge of the table being adapted to discharge the concentrates, and the curved trough being adapted to receive the tailings. 15
